FRANCIS R. DALY, OF MINNEAPOLIS, MINNESOTA.

REGISTERING APPARATUS.

Application filed March 23, 1923. Serial No. 627,226.

The invention relates to new and useful improvements in registering apparatus and is adapted to register and count the units of liquid fuel consumed by an internal combustion engine. This mechanism is particularly adapted for use in conjunction with a vacuum fuel feeding system for supplying fuel to the engine.

The function and operation of the present vacuum fuel feeding systems is well known to those skilled in this art and it may be noted that such systems employ a valve operable to open and close the inlet into the vacuum tank from the vacuum pipe leading from the tank to the usual intake manifold and also a valve operable to open and close the outlet to the atmosphere. The substantially simultaneous and opposite movement of these valves is controlled by the movement of a float in the vacuum tank. It may also be pointed out that upon each time the float moves the air valve to closed position and the vacuum valve to open position, a predetermined quantity of liquid fuel is drawn from the main supply tank to the vacuum tank. When the predetermined quantity has been so drawn to the inner vacuum tank, the float is raised and the vacuum valve is closed and the air valve is opened affording the vacuum tank communication to the atmosphere so that the drawn supply will be ported to the outer tank from which it may pass by gravity to the carburetor. This float movement continues during operation of the engine and each time that the float opens the air valve and closes the vacuum valve, a predetermined quantity of fuel is permitted to pass to the outer tank for delivery to the carburetor and subsequent consumption by the engine.

Broadly considered, this invention includes means operated by movement of the vacuum tank mechanism to count and register the fillings of the inner vacuum tank so that an accurate register may be had of the fuel consumption of the engine with which this apparatus is employed. In its preferred form such apparatus is operably connected to the air valve so that movement of such valve to closed position, during the filling operation, functions to actuate a common form of counter so that the unit of

fuel drawn to the inner vacuum tank is registered.

The object therefore of this invention is to provide an improved registry apparatus.

Other objects of the invention will more fully appear from the following description and the accompanying drawings and will be pointed out in the annexed claims.

In the accompanying drawings there has been disclosed a structure designed to carry out the objects of the invention but it is to be understood that the invention is not confined to its exact features shown as various changes may be made within the scope of the claims which follow.

In the drawings:

Figure 1 is a vertical sectional view through a common form of vacuum tank with the novel apparatus applied thereto and shown partly in side elevation and partly in vertical section.

Figure 2 is a view in side elevation of a vacuum tank with the novel apparatus in assembled relation, showing a common form of counter; and

Figure 3 is a fragmentary view similar to that of Figure 1 but showing the parts in the position assumed during the filling and counting operation.

In the selected embodiment of the invention here shown, the apparatus is connected for actuation by the usual air valve of a well-known form of vacuum fuel feeding system comprising the inner vacuum tank 4, outer tank 5, float 6, pipe 7 leading from the main fuel supply tank, pipe 8 leading from the intake manifold and adapted to be opened and closed by the vacuum valve 9, and the pipe 11 leading from the inner tank 4 to the atmosphere and adapted to be opened and closed by the usual air valve 12. When the parts are in the position shown in Figure 1, the inner vacuum tank 4 is open to the atmosphere through the unseated air valve 12 and pipe 11 so that any partial vacuum in the tank 4 is destroyed with the result that liquid fuel, usually gasoline, may drop by gravity through the bottom port 13 and its valve 14 to the outer tank 5 and thence by the pipe 15 to the usual carburetor (not necessary to be shown). However, when the level of the fuel in the inner tank drops below a pre-

determined point, the descended float 6, through its connected lever system 16, causes the valve 9 to drop to open position and the air valve 12 to drop to closed position so that the partial vacuum is created in the inner tank whereby escape of fuel through the port 13 ceases and a supply is drawn from the main supply tank through the pipe 7. When the predetermined quantity has been drawn, the elevated float reverses the two valve positions and the delivery of such quantity to the outer tank and carburetor commences. Therefore, upon each closing of the air valve or opening of the vacuum valve a predetermined quantity of fuel is drawn from the supply tank to the inner tank for delivery to the outer tank and carburetor.

Electrical means are employed, in conjunction with the air valve and a common form of counter whereby each such quantity of fuel may be registered. In the drawings there is shown a conventional representation of any of the well-known forms of counters 17 adapted to be mounted in an instrument board 18 of an automobile. The counter wheels are adapted to be turned in the usual manner by means of a ratchet wheel 19. The ratchet wheel is adapted to be actuated by a pawl 21 which is carried by a core 22 slidably mounted within the solenoid 23 carried by the base 24 suitably secured to the counter 17. A circuit for the energization of the solenoid is provided by the two wires 25 and 26 which are in circuit with the usual electric system (not necessary to be shown) of the internal combustion engine or automobile. A switch is interposed in this solenoid circuit so that, upon closure thereof, the solenoid will be energized to move the pawl 21 forwardly in order to turn the ratchet 19 one notch and thereby cause the counter to register a unit.

This electric switch is preferably such that the solenoid circuit is closed upon movement of the air valve 12 to the seated position assumed by it when the vacuum valve tank is closed to the atmosphere and a definite quantity of fuel is drawn from the main supply tank to the tank 4 of the vacuum feeding system. The switch and its controlling mechanism is preferably carried within an L-shaped housing composed of an upright portion 27 and a horizontal portion 28. The wire 25 is terminally secured to a conductor 29 while the wire 26 is similarly secured to a conductor 31. The conductors 29 and 31 are mounted normally to assume the position shown in Figure 3 wherein their respective contacts 32 and 33 are in electrical, circuit-closing position. The two conductors 29 and 31 are carried by the blocks 34 of insulation which are bolted to the housing portion 28.

The contacts 32 and 33 are adapted to be

moved and held in the circuit-opening position shown in Figure 1 by means of the insulated head 35 of the stem 36 borne by the coupling 37. The upper portion of this coupling carries the housing portion 28 in threaded engagement therewith while the lower ends of the coupling 37 is supported in threaded engagement by the tank 5.

A headed pin 38 is fixedly secured to, and upwardly projects from, the usual valve 12 although, as a matter of commercial expediency, the valve 12 and pin 38 are integrally formed. The lower end of the stem 36 is also provided with a head 39 for engagement of the head of the pin 38 upon upward unseating movements of the valve 12. The upright portion 27 of the housing is preferably hollow and is provided with ports 41 open to the atmosphere. These ports permit the escape of gasoline or other liquid fuel which tends to jet upwardly through the air valve 12, when, for any reason, the internal combustion engine runs backwardly.

As the air valve is in open position more time than it is in its lower seated position, the contacts 32 and 33 are so arranged with relation to the operating stem 36 that the upper position of the stem effects breaking of the solenoid circuit. Hence, the current is sent through the solenoid only when the air valve is seated and drawing the spring-pressed pawl 21 to right (see Figure 2), the ratchet is turned the distance of one notch and the counters correspondingly turned to register the quantity of fuel drawn to the inner tank 4 and thereafter to the carburetor. The counters may be adapted, as is well understood in this art, to register the units of fuel drawn to the engine in quarts or gallons or otherwise.

Having thus described my invention what I claim as new and desire to secure by Letters Patent, is:

1. In a vacuum fuel-feeding system comprising a filling and an emptying chamber, the filling chamber having a valve-controlled opening leading to the intake manifold of a carburetor and a valve controlled opening leading to atmosphere, and a float in the filling chamber connected with the two valves to open one of said valves as the other valve is closed; an electrically operated register, a switch for opening and closing the electric circuit to control the register, and means operatively connecting the switch with the valve controlling the communication of the filling tank with the atmosphere to actuate the switch from said valve.

2. In a vacuum fuel-feeding system comprising a filling chamber communicating with a source of supply and a point of delivery, a valve controlling communication between the filling chamber and an intake manifold of a carburetor, a valve control-

ling communication between the chamber and atmosphere, and a float in the chamber connected with the two valves to open one as the other is closed; an electrically operated register, a switch for opening and closing an electric circuit for controlling the register, and a reciprocating member asso-

ciated with the switch and actuated from the valve controlling atmosphere communication for actuating the switch to open and close the circuit.

In witness whereof, I have hereunto set my hand this 21st day of March, 1923.

FRANCIS R. DALY.
